CASH REGISTER

Ernst Breitling, Berlin-Tempelhof, Germany, assignor to The National Cash Register Company, Dayton, Ohio, a corporation of Maryland

Application October 13, 1938, Serial No. 234,748
In Germany October 30, 1937

11 Claims.

(Cl. 235—6)

This invention relates to cash registers, accounting, and like machines and pertains more particularly to totalizer selecting and positioning means therefor.

In such machines having one or more rows of totalizers, each row containing a plurality of totalizers, it is necessary to provide means for selecting and positioning the particular totalizer of a row to be used in a given machine operation so that the totalizer elements are in operative relation with the data entering and withdrawing means.

The common method now in use for positioning the selected totalizer of a row in operative relation with the data entering or data withdrawing devices consists in shifting the row of totalizers until the elements of the selected totalizer are in engageable position with said data entering or data withdrawing means. The actuating force for moving the totalizers under control of the selected key has heretofore been supplied by movement of a key or lever, or by the main operating mechanism.

It is the principal object of this invention to provide means whereby the depression of the selecting key moves the totalizer or totalizers associated therewith into engageable position with the data entering and data withdrawing devices, special mechanism of the machine supplying the power for the positioning movement.

Another object of the invention is to provide novel power operated means for selecting a totalizer before the machine commences its operation.

Another object of the invention is to provide novel mechanism to return shifted totalizers to a normal position at the conclusion of a machine operation.

Another object of the invention is to provide a power source to movably select a totalizer which power source subsequently operates to release the machine for its main operation.

Another object of the invention is to provide power means to position a key-selected totalizer, said power means being potentially conditioned by the previous machine operation.

The invention is disclosed as applied to a machine of the type disclosed in United States Patent No. 2,101,636, issued to Ernst Breitling and Hans Schwenk, but the invention is not limited in application to that particular machine, as it is adaptable to machines of similar character.

With these and incidental objects in view, the invention includes certain novel features of construction and combinations of parts, the essen-

tial elements of which are set forth in appended claims and a preferred form or embodiment of which is hereinafter described with reference to the drawings which accompany and form a part of this specification.

In the drawings:

Fig. 1 is a vertical section of the machine from front to rear, to the right of the transaction key bank, looking toward the left.

Fig. 2 is a diagrammatical front view of the mechanism shown in Fig. 1, along the line 2—2 of Fig. 1.

Fig. 3 is a detail showing the machine release mechanism.

Key mechanism

A bank of depressible totalizer selecting keys 11 and 12 (Fig. 1) are slidably mounted in frame 13 and held in normal depressible position by springs, not shown. Each key is provided with a pin 14 adapted to cooperate with beveled surfaces on a sliding plate 15, mounted on studs 16 and 17, in such a manner that depressing an "11" key causes the plate 15 to move upwardly unless then in that position, and depressing a "12" key causes it to move downwardly unless then in that position. Therefore, if the last key depressed is an "11" key the plate 15 will be in the upper position, and if the last key depressed is a "12" key the plate 15 will be in the lower position. A second sliding plate 18, mounted on studs 16 and 17, is normally retained in the upward position, shown in Fig. 1, by a spring 19 pulling said plate upwardly through a link 20. Plate 18 is forced downwardly against the tension of spring 19 when either an "11" key or a "12" key is depressed, due to the stud 14 of the depressed key entering a camming slot in said plate 18.

Mounted loosely on shaft 21 is a plate 22, and mounted loosely on shaft 23 is a plate 24, said plates 22 and 24 being connected together by link 25 in such a manner that both plates must rotate in the same direction. The plates 22 and 24 are constantly urged in a clockwise direction by spring 26. Shoulder 27 of plate 24 normally rests against the arm 28 of a bell crank lever 29 mounted loosely on stud 30, preventing the clockwise motion of plates 22 and 24. The other arm of bell crank lever 29 is pivotally connected to link 20 before mentioned. Under these conditions, whenever a key "11" or "12" is depressed, lever 29 is moved clockwise by means of link 20, which clockwise motion allows shoulder 27 to bypass arm 28 allowing plates 22 and 24 to turn clockwise under the influence of spring 26 until shoulder 31 on plate 24 strikes arm 28. The

tension of the spring 26 is restored at the end of each machine operation, for use in the next transaction, through the rotation of cam 32 pinned to the main drive shaft 33. The shaft 33 making one rotation each machine operation causes lever 34 to be rocked clockwise near the end of the cycle which motion, by means of a pin and slot connection, rocks plates 22 and 24 counterclockwise allowing arm 28 to engage shoulder 27 under action of spring 19, if the operator is no longer holding the key down, thus restoring the key mechanism to normal position. The restoring action tensions spring 26 for the next machine operation.

If a key is held down by the operator throughout the machine operation so that arm 28 is not positioned to catch shoulder 27, pawl 39 (Fig. 1), loosely mounted on stud 30, which normally rides surface 40 of plate 24 or is held away from surface 40 by pin 41, is allowed to catch surface 42, as plate 24 is rocked counterclockwise slightly beyond normal position on the restoring motion, thus preventing a repeat operation. On the key being finally released by the operator, arm 28 is positioned to catch shoulder 27 before pawl 39 leaves surface 42.

The rocking of plate 22 clockwise operates the machine release mechanism and the totalizer selecting and positioning mechanism.

Machine release

Secured on shaft 35 (Figs. 1 and 3) is a lever 36 (Fig. 1) connected to plate 22 by a pin and slot connection in such a manner that on depression of a key, which allows plate 22 to turn clockwise under the action of spring 26, lever 36 will be moved so as to cause shaft 35 to rock counterclockwise. Also secured to shaft 35 is a lever 37 (Fig. 3) having a toe 38 normally blocking the clockwise movement of lever 46 around its supporting bearing 47, as urged by spring 48. When shaft 35 is rocked counterclockwise by depression of a key 11 or 12 (Fig. 1), toe 38 (Fig. 3) is withdrawn from shoulder 49 allowing lever 46 to rock clockwise. A link 51 is slidably mounted at one end on shaft 35 by means of a bifurcation, and is pivoted at its other end to the upper extending arm 53 of a four armed lever 57 rotatably mounted on shaft 54. Link 51 supports a roller 50 which normally rests against surface 52 of lever 46. As lever 46 rocks clockwise, under action of spring 48, springs 55 and 56 are allowed to pull link 51 to the left as surface 52 moves out of the way. The movement of link 51 rocks lever 57 counterclockwise, causing arm 53 to be removed from the path of lug 59 extending from wheel 60, which wheel is secured to the main drive shaft 33, allowing the shaft to be turned counterclockwise as the machine is operated. On completion of the rotation of the main drive shaft 33 stud 61 causes clockwise rocking of lever 57 which moves link 51 to the right causing stud 62 to bear against shoulder 63 of lever 46 forcing it counterclockwise so as to be latched by lever 37 as shaft 35 is rocked clockwise when plate 22 (Fig. 1) is rocked counterclockwise at the completion of the machine operation.

Thus a potential source of energy, consisting of a spring 26 (Fig. 1) tensioned by the previous machine operation, serves to unlock the machine for operation upon depressing any one of the keys "11" or "12."

The same source of energy at the same time

through the turning of plate 22 positions the totalizers under selection of the key depressed.

Totalizer selecting and positioning mechanism

Plate 15 (Fig. 1) is provided with a beveled surface for each key "11" and "12." These beveled surfaces cooperate with the pins 14 so that when a "12" key is depressed the plate 15 is moved to the down position, if not there at the time, and when an "11" key is depressed the plate 15 is moved to the up position if not there at the time. The plate 15 is shown in the illustration in the down position it assumes after a "12" key has been last depressed. The purpose of this selective movement of plate 15 is to block or permit the counter clockwise motion of lever 64 around stud 65 by causing shoulder 66 on plate 15 to be positioned or not be positioned in the path of movement of toe 67 on lever 64. When the plate 15 assumes the down position, caused by last depressing a "12" key, lever 64 is prevented from rocking counterclockwise, and when plate 15 is in the up position, it assumes when an "11" key is last depressed, the lever 64 is permitted to be rocked counterclockwise.

Rotatably mounted on shaft 21 is a lever 68 having an upper extending arm and a lower extending arm. Pivotally mounted on stud 69 secured on the upper extending arm of lever 68 is a link-lever 70 having a pin 71 engaging a bifurcation of lever 64, and a pin 72 engaging a bifurcation on plate 22. On the clockwise rocking of plate 22 link-lever 70 acts as an idly moving link if lever 64 is free to move, stud 69 acting as a pivot, but if lever 64 is kept from moving by the blocking action of shoulder 66 on plate 15 then pin 71 is held fixed as a center and lever 68 is rocked counterclockwise as plate 22 rocks clockwise.

Therefore if an "11" key is controlling the operation by being depressed, lever 68 gets no motion and if a "12" key is controlling, lever 68 is rocked counterclockwise.

Pins 13 in the stems of the "11" keys cooperate with bifurcations 74 in lever 68 to keep lever 68 from chance movement when an "11" key is depressed. When an "11" key is depressed the lever 68 is kept set as shown in Fig. 1, that being the position assumed at the end of a machine operation as will be explained. The lower extending arm 75 of lever 68 has a bifurcation cooperating with a pin 76 on one arm of a three armed lever 77 rotatably mounted on shaft 78.

Arms 79 and 80 of lever 77 have toothed ends cooperating with teeth on drum cams 81 and 82 rotatably mounted on frame supported studs 83 and 84. Drum cam 81 (Figs. 1 and 2) cooperates with cam followers 85 and 86 secured to a yoke 43, and drum cam 82 cooperates with cam followers 87 and 88 which are secured to a yoke 44.

Integral with yoke 43 are hubs 107 and 108 (Fig. 1) which hubs bear rotatable shafts 89 and 90. Integral with yoke 44 are hubs 109 and 110 which bear rotatable shafts 91 and 92. The hubs 107, 108, 109, and 110 are themselves loosely mounted in frame 111 (Fig. 3) so that shafts 89, 90, 91, and 92 may be rocked, and hubs 107, 108, 109, and 110 shifted. Fig. 2 shows the method of mounting the totalizers associated with shaft 91. Pinned to shaft 91 are two arms, only the right arm 112 being shown. Mounted between said arms is the totalizer shaft 95 bearing thereon the rotatably mounted interspersed totalizer wheels 101, 102, 103, 104, 105, and 106, said wheels representing the lower three orders

of two totalizers. Shifting shaft 91 selectively

positions the wheels of one or the other of the totalizers opposite the data-entering and data-withdrawing differential elements 98, 99, and 100. The hub 109 is held between the arm 112 and a lever 97 both of which are pinned to shaft 91, so that when yoke 44 is moved by cam 82 the shaft 91 is shifted. The hubs 108, 107, and 110 are mounted in the same manner. The totalizer so selected is engaged with the differential elements by rocking shaft 91. To accomplish such rocking of shaft 91 a lever 97 is pinned to the right end thereof to be selectively operated. The totalizer shafts 93, 94 and 96 are supported similarly to shaft 95 in arms pinned on their respective totalizer frame shafts 90, 89, and 92 so that a totalizer in each of the rows of totalizers may be selected and swung into engagement and out of engagement with their respective differential elements by turning shafts 90, 89, and 92 by a suitable totalizer engaging mechanism such as that illustrated in United States Patent No. 2,101,636 to which reference has been made.

Whenever the drum cams 81 and 82 are turned, all of the rows of totalizers are positioned alike to position the totalizers representing the "11" or the "12" keys depending on which key is depressed.

The three differential members 98, 99, and 100 (Fig. 2), representing the right three key banks for registering amounts, are shown positioned so they will engage with the totalizer wheels 101, 102, and 103 on totalizer row 95, which wheels are associated with the "11" keys. Totalizer wheels 104, 105, and 106 represent the "12" keys and are placed in engageable position with the differential members when cam 82 is turned under the selective action of the "12" keys.

Near the end of the machine operation plate 22 (Fig. 1) is turned counterclockwise by lever 34 (Fig. 1). If lever 68 has been displaced during the machine operation from the normal position shown, by depression of a "12" key, the lever 64 not having moved is unable to turn clockwise more than slightly from the position shown in Fig. 1 as it is in the same plane as plate 18 (Fig. 2) thus causing pin 71 to act as a pivot as lever 70 is turned clockwise forcing lever 68 to the home position shown in Fig. 1. Thus, the totalizer associated with the "11" keys is normally in engageable position with the differential members. When a machine operation is controlled by an "11" key the lever 64 is idly moved counterclockwise at the beginning of the machine operation and clockwise at the end of the machine operation, causing no movement of lever 68.

The machine release is so timed that surface 38 (Fig. 3) does not free lever 46 until the plate 22 is near its maximum clockwise movement assuring the selected totalizers are in engageable position before the machine commences its operation.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described having data entering and data withdrawing means; and a row of totalizers having thereon two totalizers one of which is normally positioned to be engaged

with the said data entering and data withdrawing means said totalizer row being shiftable so as to bring the totalizer not normally positioned to position for data entering the data withdrawing, the combination of a plurality of keys part of which are associated with the normally positioned totalizer and part of which are associated with the totalizer not normally positioned; a selector slide movable in one direction by depressing the keys associated with the totalizer normally in position and movable in the other direction by depressing the keys associated with the totalizer not normally in position said slide remaining in the position given it by the last key depressed until moved in the other direction by a key of the other group; a plate having a uniform power actuated movement when any key is depressed; and a totalizer selecting differential means actuated by the plate under control of the selector slide to shift the totalizer rows if the normally positioned totalizer is not the one associated with the depressed key.

2. In a machine of the class described having a main operating mechanism; data entering and data withdrawing means; and a row of interspersed totalizers having thereon two totalizers one of which is normally positioned to be engaged with the said data entering and data withdrawing means said totalizer row being shiftable so as to bring the totalizer not normally positioned to position for data entering and data withdrawing, the combination of a plurality of keys part of which are associated with the normally positioned totalizers and part of which are associated with the totalizer not normally positioned; a selector slide movable in one direction by depressing the keys associated with the totalizer normally in position and movable in the other direction by depressing the keys associated with the totalizer not normally in position said slide remaining in the position given it by the last key depressed until moved in the other direction by a key of the other group; a plate having a uniform power actuated movement when any key is depressed; and a totalizer selecting differential means actuated by the plate under control of the selector slide to shift the totalizer row if the normally positioned totalizer is not the one associated with the depressed key; and means comprising a cam and lever moved by the main operating mechanism at the conclusion of a machine operation to return the totalizer row and totalizer selecting differential to normal position by restoring the plate to its original position.

3. In a machine of the class described capable of performing cycles of operation, the combination of a bank of depressible keys divided into two groups; a source of power means to render the source of power potentially available, said means operated during the previous cycle of operation; a row of totalizers, each totalizer representing a group of said keys, said row being shiftable to select a totalizer for actuation; means whereby the depression of a key renders the power means operative before the commencement of the ensuing cycle of operation; a movable member actuated by the power means; and means set under control of the keys and cooperating with the movable member to shift to actuating position the totalizer representing the group to which the depressed key belongs.

4. In a machine of the class described capable of performing cycles of operation and having means to block the machine against operation

and a plurality of totalizers any one of which may be positioned for actuation, the combination of a plurality of control keys divided into groups, each group representing a totalizer; means to unblock the machine for operation by operating any one of the keys; a totalizer selecting control means operable by any key according to the grouping of the selected key; and means actuated by the unblocking means under control of the totalizer selecting control means, when said unblocking means is operated, for positioning for actuation the totalizer associated with the grouping of the depressed key.

5. In a machine of the class described capable of performing cycles of operation and having means to block the machine against operation; a shiftably mounted row of totalizers having two totalizers one of which is normally positioned to be actuated; and means to shift the other totalizer to said actuating position, the combination of a plurality of keys; normally ineffective power means for actuating the shifting means; means rendering the power means effective on operation of a key; and means differentially set by certain of the keys to cause the effective power means to operate the shifting means.

6. In a machine of the class described capable of performing cycles of operation and having interspersed totalizers; means blocking the machine against operation; and machine blocking release means, the combination of a plurality of control keys divided into groups, the members of each group being associated with a certain totalizer and each of said keys operating the release means; a differentially settable control set in accordance with the grouping of a depressed key; and means actuated by the release means when rendered operative to position for actuation under control of the differentially settable means the totalizer associated with the operated key, before the machine is unblocked.

7. In a machine of the class described, the combination of a plurality of totalizers; a means to position a selected totalizer for actuation; a main operating means; a plurality of keys; a means to block the machine against operation; and a machine block release means rendered effective by depressing any key; with means differentially operated by operating the keys; and means controlled by the differentially operated means and actuated by the release means to position for actuation the totalizer associated with the depressed key.

8. In a machine of the class described, the combination of means to block the machine against operation; a plurality of shiftably mounted totalizers; means to shift a selected totalizer into operative position; a plurality of keys to

control the operation of the shifting means to determine which of the plurality of totalizers is to be moved into operable position by the shifting means; means for operating the shifting means and simultaneously releasing the blocking means upon depression of a key before the operation of the machine commences; and means operable during one machine operation to condition the means for operating the shifting means for operation for the next succeeding machine operation.

9. In a normally locked machine of the class described, the combination of a row of interspersed totalizers; means to shift the row of totalizers to select a totalizer for operation; machine release means; keys operable to determine the selection of a totalizer and to cause the machine release means to operate; and means operated by the machine release means to operate the totalizer row shifting means to position the selected totalizer into its operating position before the machine is completely released.

10. In a machine of the class described, the combination of a plurality of totalizers; a plurality of keys divided into groups, each key of a group being associated with a certain one of the plurality of totalizers; means to normally lock the machine against operation; means connected to the locking means and operable by depression of any one of said keys to release the machine for operation; and means actuated by the last-named means and controlled by the key which is depressed to select the totalizer associated with the depressed key prior to the complete release of the machine.

11. In a machine of the class described, the combination of a row of interspersed totalizers; a plurality of depressible control keys divided into groups, the keys of each group being associated with a certain totalizer of the row of totalizers; means to move the group of totalizers to select a totalizer for operation; a source of potential energy; means for normally blocking the machine against operation; means operable by the source of potential energy to release the blocking means; and a plurality of connections between the control keys and the last-named means, one of said connections operable by the depression of a key to release the last-named means for operation by the potential power and the other connection being operable by the last-named means under control of a depressed key to control the extent of movement of the moving means to select the totalizer associated with the depressed key prior to the release of the blocking means.

ERNST BREITLING.

CERTIFICATE OF CORRECTION.

Patent No. 2,266,845.

December 23, 1941.

ERNST BREITLING.

It is hereby certified that error appears in the printed specification of the above numbered patent requiring correction as follows: Page 3, second column, line 4, claim 1, for "the" read --and--; and line 20, same claim, for "rows" read --row--; line 58, claim 3, after "power" and before "means" insert a semicolon; and that the said Letters Patent should be read with this correction therein that the same may conform to the record of the case in the Patent Office.

Signed and sealed this 10th day of February, A. D. 1942.

Henry Van Arsdale,
(Seal) Acting Commissioner of Patents.
